UNITED STATES PATENT OFFICE.

JAMES A. JOYCE, OF CLEVELAND, OHIO, ASSIGNOR TO THE AMERICAN MINE DOOR COMPANY, OF CLEVELAND, OHIO.

AUTOMATIC MINE-GATE.

SPECIFICATION forming part of Letters Patent No. 783,282, dated February 21, 1905.

Application filed August 14, 1903. Serial No. 169,449.

To all whom it may concern:

Be it known that I, JAMES A. JOYCE, residing at Cleveland, county of Cuyahoga, and State of Ohio, have invented certain new and useful Improvements in Mine-Gates; and I do hereby declare the following to be a full, clear, and exact description of the invention, such as will enable others skilled in the art to which it appertains to make and use the same.

10 In gates for controlling the drafts of air in the entries, passages, and drifts of mines it is desirable to secure quick action of the gate in opening and closing—in opening to prevent the car from running against and injuring the 15 gate and in closing so as not to appreciably interrupt the predetermined currents of air necessary to ventilate the working parts of the mine. Simplicity of construction in the gate-operating mechanism is likewise an item of 20 vital consequence.

The gate is of the type adapted to fold upward in puckles and is attached overhead to a cross-piece and strengthened transversely by bars, slats, or the like.

25 For a full description of the invention and the merits thereof and also to acquire a knowledge of the details of construction of the means for effecting the result reference is to be had to the following description and the drawings 30 hereto attached.

While the essential and characteristic features of the invention are necessarily susceptible of modification, still the preferred embodiment of the invention is illustrated in the 35 accompanying drawings, in which—

Figure I is a top view of the gate and the operating mechanism. Fig. II is a side elevation of the gate and the operating mechanism. Dotted lines show closed position.

40 A main gate-frame is provided comprising the uprights 2 and the cross-piece 3. Adjacent this frame is a movable frame upon which are pivotally secured the gate-arms 8, which are also supported and guided from the 45 mine-gate frame, as will hereinafter appear. This movable frame consists of rods 6 and a cross-piece 7 at top, which is securely fastened to the rods 6. The lower ends of rods 6 are securely fastened to a rock-shaft 25,

which is pivotally mounted in bearings 26. 50 At the upper end of this frame is pivotally fastened the upper end of the gate-arms 8, while at the lower end of the gate-arms 8 is securely fastened the flexible gate 4, which is provided with a stiffening-piece 1 at bottom for 55 keeping the gate in line and also securing the lower ends of the gate-arms 8 together. The said gate-arms 8 are constructed with one long member having connected thereto two short brace members, either straight or curved; but 60 in this case I have shown them straight. The two short brace members are fastened to the long member at convenient points, and these two braces are fastened together at a convenient point 9. At or near this point there is a 65 pin upon which there is mounted a roller 9^a. There are two of these rollers 9^a, located at the point of fastening of the brace members for each arm 8. These rollers may be of any convenient shape and are adapted to roll 70 within guide members 10 10, one of which is provided for each roller 9^a. These guides 10 are curved to permit of the swing of the pivoted brace members and are supported by arms 10^a, which extend in pairs from each of 75 the uprights 2 2 of the main gate-frame. The arrangement of the rollers 9^a whereby they travel in the curved guides 10 is such as to constitute slidable pivots for the braces of 80 the gate-arms, and the changing of the pivotal point of the braces allows a backward-and-forward movement of the point at which the gate-arms are pivoted to the movable frame. This action of the brace members as guided in their movement by the curved 85 guides in which engage the rollers 9^a is what is termed "slidable" in the sense in which I use this term with reference to the changing pivotal point. The upper end of the gate-arm 8 is extended to receive an adjustable counterweight 11, which counterbalances the gate-arms, whereby the actuation of the gate is 90 rendered comparatively easy.

When the gate is installed, the rod 6 is made to incline toward the gate-frame, which allows the gate-arms to hang vertically down, unfolding the gate-curtain.

The method of automatically operating the

gate is by a series of rock-shafts 12, which are located at convenient places on opposite sides of the plane of the gate and connected for simultaneous operation, the shafts on one side of the gate rotating in opposite direction to the shafts on the other side.

The levers 13 and 14 are securely fastened to the rock-shafts 12. The ends of levers 14 are pivotally connected to the depressible trip-rails 16. Similar depressible trip-rails 17 are normally inclined and pivotally supported at their outer ends upon a tie or other suitable means and have depending arms 18 at their inner ends connected by links 19 with a lug on the end of trip-rails 16 to allow for the relative play between the adjacent ends of the trip-rails when in operation.

Levers 13 are keyed or otherwise secured to the outer ends of rock-shafts 12 and are connected in a manner presently to be described, so as to effect a simultaneous operation of the rock-shafts.

The levers 13, secured to the rock-shafts upon opposite sides of the gate, project in opposite directions, and links 20 are pivoted midway of their ends to all except the outermost lever 13. To the outermost levers 13 are connected rods 21, which are secured to the links 20, while these links are connected by rods 22, extending between the same. The innermost levers 13 are each connected with the rod 6 of the movable frame, one being connected therewith by the rod 23 just above the rock-shaft 25, while the other is connected thereto by the rod 24, secured to the rod 6, just below the said rock-shaft.

The rods, levers, links, and rock-shafts on the right-hand side of the gate are of similar construction to those just described on the left-hand side of the gate, only that they operate in opposite direction to the same.

All of the rods 21 22 23 24 may be provided with turnbuckles for adjustment, so as to allow for variation in assembling the parts when installing the gates in a mine.

The links 20 prevent straining of the rods or connections attached thereto when the rock-shafts move in their bearings to effect an actuation of the gate.

The rock-shafts 12 are mounted alike in bearings 27, which bearings are securely fastened to supports 28. The rock-shafts are provided with collars 29, which are movable on the rock-shafts and are provided with set-screws for holding the collars in place on the rock-shafts.

When the rock-shafts have been permanently adjusted, the collars 29 are slid along the rock-shafts up to the bearings 27 and secured in place against the same by the set-screws, which prevents the rock-shafts from moving longitudinally in the bearings.

The gate-arms 8 are normally inclined downward or nearly vertical, as shown by dotted

lines. When a car-wheel runs on the depressible trip-rails 16 and 17, thereby depressing the same and actuating the levers, rods, and rock-shafts, the movable frame 6 and 7 is moved back from the gate-frame 2 and 3. This backward movement of the movable frame causes the gate-arms 8 to move upwardly and back to substantially a horizontal position, thereby causing the flexible gate 4 to fold up and be supported on the said gate-arms 8.

Having thus described the invention, what is claimed as new is—

1. A flexible mine-gate, suspended from a frame, slidably-pivoted arms extending beneath the gate for folding it upward and supporting the folds, and actuating mechanism, substantially as shown and described.

2. A device of the type set forth, comprising a main gate-frame, a movable frame pivoted at one end adjacent said gate-frame, slidably-pivoted arms secured thereto, a flexible mine-gate carried thereby, a guide for supporting the slidably-pivoted portion of said arms, and actuating mechanism pivotally connected to the movable frame, substantially as set forth.

3. A flexible mine-gate, a frame carrying the same, gate-arms extending normally downward and substantially vertical, a counterweight for counterbalancing the gate and gate-arms, a movable frame pivotally supporting the upper ends of the gate-arms, a slidably-pivoted support for the gate-arms, and actuating mechanism, substantially as described.

4. A flexible mine-gate suspended from a frame, a gate-arm extending normally downward and nearly vertical, and across the lower end of the gate, a movable frame pivotally supporting the upper end of the gate-arm, a slidably-pivoted support for the gate-arm acting in combination with the movable frame, a depressible trip-rail adapted to be actuated by a moving car and connections between the same and movable frame, substantially as set forth.

5. In a device of the character described, a main gate-frame, a flexible gate, gate-arms carrying the same, brace members secured to said gate-arms forming a slidable pivot for said arms, means carried by the main frame to guide the said slidable pivot of the arms, a movable frame pivotally mounted at its lower end near the gate-frame and being pivotally connected to the gate-arms at its upper end, and means for actuating said movable frame to actuate said arms, substantially as and for the purpose set forth.

In testimony whereof I have affixed my signature in presence of two witnesses.

JAMES A. JOYCE.
